UNITED STATES PATENT OFFICE

CHARLES W. GERLACH, OF WHEATON, ILLINOIS, ASSIGNOR TO CHICAGO MILL AND LUMBER CORPORATION, OF CHICAGO, ILLINOIS, A CORPORATION OF DELAWARE

PACKING DEVICE

Application filed February 20, 1930. Serial No. 429,846.

This invention relates to packing devices and more particularly to a construction and arrangement for economically and quickly packing fine cabinets and similar articles of furniture. One object of the invention is to provide a construction of this type which will provide an extremely safe and efficient packing device which will permit the most expensive and highly finished cabinets to be handled and shipped with a maximum amount of safety. A further object of the invention is to provide an improved spacing construction for maintaining the cabinet or other article spaced from the interior of the packing case and at the same time to simplify the method of packing.

Another object of my invention is to provide a packing case for a cabinet or other article, which can be opened by an unskilled workman, with an internal reinforcing and spacing frame which can be opened sufficiently to permit removal of the cabinet after one of the casing walls has been released without the use of a tool. Still another object is to provide a packing case with an internal frame that can be opened and replaced for unpacking and repacking without damage to the frame members.

To these and other ends the invention resides in certain improvements and combinations of parts, all as will be hereinafter more fully described, the novel features being pointed out in the claims at the end of the specification.

35 In the drawings illustrating a preferred embodiment of the invention,

Figure 1 is a front elevation of a packing case with one side removed and showing the manner of spacing a cabinet therein;

40 Figure 2 is a perspective sectional view of the packing case taken substantially along line 2—2 of Figure 1; and

45 Figure 3 is a fragmentary detail view of one form of packing material used with the present invention.

Similar reference numerals throughout the several views indicate the same parts.

The present embodiment of the invention provides a safe and effective packing construction of a simple and readily assembled

form which is particularly adapted for use with fine articles of furniture such as radio and phonograph cabinets and similar articles.

Referring more particularly to the drawings there is shown at 5 a packing case of more or less conventional form which comprises a top wall 6, bottom wall 7 and side walls 8, 9, 10 and 11. The top, bottom and side walls may be made in various ways and of various sorts of materials but, in the present instance, they are illustrated as panelled members with a main wall portion of thin material such as three ply veneer or plywood and a frame to which the main wall portion is nailed. As this construction is more or less common it requires no further description.

The top, bottom and side walls are constructed in proper sizes at the factory and are shipped to the user in knock-down condition in order to conserve space in shipment and storage.

In order to safely carry a cabinet within a packing case such as illustrated means are provided for spacing it from contact with the interior of the walls. For this purpose the present invention provides a spacing means in the form what may be termed an open collar comprising a plurality of sections or spacing members 12, 13, 14 and 15 80 certain of which spacing members are secured in place against the side walls of the packing case and certain others of which are preferably unsecured but are maintained in place by reason of an interfitting arrangement 85 between the ends of the spacing members.

In the present instance spacing members 12 and 13 are preferably secured in place against the side walls 8 and 9 in any desired manner as by driving nails or staples through the side walls, from their outer side, and into the spacing members 12 and 13. The spacing members may be secured to the side walls either at the factory of the manufacturer or at the factory of the user, whichever method 95 may be deemed preferable under existing conditions.

The spacing members are preferably formed so as to be interfitted with each other at their ends and for this purpose, in the 100

present embodiment of the invention, the spacing members 12 and 13 are grooved at their ends as shown at 16 and the members 14 and 15 are provided with a tongue 17 at their ends adapted to fit within the grooves 16. Obviously, this arrangement is not always necessary as it is equally feasible to reverse the arrangement just described, or each spacing member could be provided with a tongue at one end and a groove at the other end to cooperate with complementary elements on an adjacent spacing member.

As the spacing members are designed to hold the cabinet within the packing case it is desirable to provide means for preventing marring of the cabinet by these spacing members. In the present instance this means comprises a packing strip 18 preferably in the form of a length of fibre board or strong paper to one side of which is secured a layer of soft nonscratching material such as crinkled tissue paper indicated at 19. Any soft packing material may be used for this purpose but this particular assembly of a soft crinkled paper with a strong fibre sheet has been found especially desirable due to its cheapness and the ease with which it may be applied. This packing strip is applied to a cabinet by extending it around all the finished faces and tacking it to the back of the cabinet if the back is unfinished. Where the back of the cabinet is also finished the strip can be held in place by wrapping it around so as to overlap at a point where the strip, by reason of adjacent projecting portions of the cabinet, does not contact the finished surface thereof. At this point the strip may be secured in any desired manner as by means of stitching with a short length of cord.

In order to space the top of the cabinet from the top of the packing case a spacing member 20 may be employed with a piece of packing strip 18 placed therebeneath so as to protect the surface of the cabinet.

A preferred method of assembling a packing case with the device of the present invention will now be described. The user will select the desired sizes of top, bottom and side walls from his storage supply of knock-down parts. If the side walls do not have spacing members secured thereto the user will proceed to secure these spacing members, such as members 12 and 13, to the respective side walls 8 and 9. The top and bottom of the packing case are next assembled with the side walls 8 and 9 after which the case is ready to receive one of the other side walls, such as the rear side wall 10. Before securing the side wall 10 the workman will position the spacing member 14 so that its tongue portions 17, 17 will be received within the grooves 16, 16 at the respective ends of spacing members 12 and 13. When spacing member 14 is so assembled with the spacing

members 12 and 13 it will be held against movement in three directions.

When the spacing member 14 has been so positioned the workman will next secure the rear side wall 10 in place for assembly which may be done by nailing it to the edges of top wall 6, bottom wall 7 and the two side walls 8 and 9. When the rear side wall 10 is so secured to the other walls it will prevent the spacing member 14 from movement in an outward direction as will be obvious. Thus, the spacing member 14 is held in position without the necessity of its being nailed or otherwise directly secured to the other spacing members 12 and 13 or to any of the walls.

Having assembled the packing case thus far the workman next applies packing strip 18 on to the cabinet as previously described and in the position indicated in Fig. 1. When the cabinet has been placed in the packing case the strip 18 will lie between the cabinet and the spacing members and protect the finished surface from being marred by direct contact with such members.

When the packing strip is in place on the cabinet the workman will then slide the cabinet into the packing case through the open front, see Fig. 1. With the cabinet thus assembled within the packing case the workman next fits into place the remaining spacing member 15 so that its tongues 17, 17 will be received in grooves 16, 16. The front side wall 11 will next be nailed into place thus securing spacing member 15 from movement in outward direction. This spacing member, as in the case of spacing member 14, will be held in proper position within the packing case without nailing or otherwise directly securing it either to the adjoining spacing members or to any of the walls.

As indicated in Fig. 1, two sets of spacing members may be employed, one set being disposed near the upper end of the cabinet and the other set being disposed near the lower end of the cabinet proper and above the point where the legs are joined to it.

Means may be employed, if desired, for supporting the cabinet so that no weight will be borne by its legs. A suitable arrangement for this purpose is shown in my prior Patent No. 1,694,973, granted Dec. 11, 1928.

After the cabinet has been placed in position within the packing case and before the case is entirely sealed, the spacing member 20 will be inserted in place to space the top of the cabinet from the top 6 of the packing case. As before described, a piece of packing material 18 will be employed to lie between the spacing member 20 and the top of the cabinet.

The method of unpacking a cabinet which has been packed in the manner herein described is quite simple. All that is necessary to be done is to carefully pry loose one

of the side walls (either the front or the back) from its attachment to the adjoining walls. When this has been done it is only necessary to remove the spacing member or members 15 and slide the cabinet out of the packing case and next remove the packing strips 18 after which the cabinet is ready to be put into use.

From the foregoing it is apparent that the present invention provides a packing case and a method of packing making it possible to both pack and carry a cabinet with the utmost degree of safety. Since the spacing members require no nails or other positive securing means to hold them in assembled relation with each other there is much less likelihood of marring the finish of the cabinet than in the case where nails or other securing means are employed. The packing strip which lies between the spacing members and the cabinet may be formed from inexpensive materials and may be quickly secured in place with a minimum of labor to provide an effective protection for the finished sides of a cabinet. The present packing case, furthermore, is extremely easy to unpack and, since the unpacking operation requires no nails or screws to be withdrawn other than the nails or screws which hold the front wall in place, there is less likelihood of marring the cabinet than where a hammer or screw-driver is necessary in order to remove the spacing members from contact with the cabinet.

The construction and method of packing of the present invention are quite advantageous in the radio industry. The manufacture of radio receiving units and radio cabinets is generally carried on by separate concerns. The cabinet manufacturer makes a cabinet designed to fit a particular radio unit; this cabinet is then shipped to the jobber or wholesaler who also receives the radio units to be fitted into the cabinets. Thus, by reason of the extreme ease and facility with which a cabinet may be unpacked and then repacked, the jobbers problem of assembling the radio unit with the cabinet is greatly simplified. It is but the matter of a few minutes to remove the front wall of a packing case containing an empty cabinet, then to withdraw the cabinet, removing its packing strip or strips, inserting the radio unit within the cabinet, then repacking the cabinet and sealing it within its packing case.

It is apparent that the operations involved in assembling a radio unit with a cabinet may be carried out by workmen who are relatively unskilled. This is due largely to the fact that it is possible to remove the spacing members from their contact with the cabinet without withdrawing nails or removing screws or similar fastening means.

In the particular embodiment of my invention as illustrated, I have referred to cer-

tain walls of the case as top and bottom walls, and the others as side walls. It is obvious that the terms of the claims are not to be thus limited. Any wall section, for example the top section, may be the one secured in position last, and this may be termed the closure wall.

While the present description sets forth a preferred embodiment of the invention, numerous changes may be made in the construction and process of assembly without departing from the spirit of the invention, and it is therefore desired that the present embodiment be considered in all respects as illustrative and not restrictive, reference being had to the appended claims rather than to the foregoing description to indicate the scope of the invention.

I claim:

1. A packing construction for cabinets comprising a top, bottom and two side walls, a spacing member secured in place against each of the side walls, an additional spacing member adapted to be interfitted with the adjacent ends of said first mentioned spacing members whereby said additional spacing member is held from movement inwardly, upwardly and downwardly, and an additional side wall adapted to be secured in place against said top, bottom and first mentioned side walls, said additional side wall serving as the sole means for holding said last mentioned spacing member from outward movement.

2. A packing construction for cabinets comprising a top, bottom and two side walls, a spacing member secured in place against the inside of each of the side walls, an additional spacing member extending between corresponding ends of the first mentioned spacing members and having its ends interfitted with the respective adjacent ends of said first mentioned spacing members to prevent displacement of the said ends in three directions, and an additional side wall adapted to be secured in place against said top, bottom and first mentioned side walls and serving as the sole means for preventing displacement of said additional spacing member in a fourth direction.

3. A packing construction for cabinets comprising a top, bottom and two side walls, a spacing member secured to the inside of each side wall, an additional spacing member adapted to have its ends interfitted with adjacent ends of said first mentioned spacing members by a tongue and groove arrangement whereby said additional spacing member will be held from displacement in all but an outward direction, and an additional side wall secured against said top, bottom and first mentioned side walls and serving as the sole means to prevent outward movement of the additional spacing member.

4. A packing construction for cabinets

comprising a top, bottom, and two side walls, spacing members secured to both of said side walls, horizontal grooves in the ends of said spacing members, an additional spacing member provided with tongues at its ends adapted respectively to engage within the grooves of adjacent ends of said first mentioned spacing members and hold said additional spacing member from movement in all but an outward direction, and a third side wall adapted to be secured in place against said top, bottom and first mentioned side walls thereby serving as the sole means to prevent outward movement of said additional spacing member.

5. A method of packing cabinets which comprises providing a sectional, six wall packing case, securing two opposed side walls respectively to the top and bottom walls of said packing case, securing a grooved spacing member to the inner side of each side wall, assembling a tongued spacing member with said first mentioned spacing members so that the tongues thereof enter the grooves of said first mentioned spacing members, sliding a cabinet into place within said packing case, next assembling a fourth tongued spacing member with its tongues received into the grooves of said side wall spacing members, and finally securing the fourth side wall in place against the top, bottom, and first mentioned side walls.

6. A packing case for cabinets or similar articles of furniture comprising six wall sections adapted to completely enclose said cabinet, one of said wall sections being removable and constituting a closure wall, and means associated with said packing case for maintaining said cabinet spaced from at least some 10 of said wall sections, said means comprising a spacing member secured to each of two oppositely disposed wall sections, an additional spacing member adapted to space said cabinet from said closure wall and extending 15 between corresponding sides of said oppositely disposed wall sections which have spacing members secured thereto, the respective adjacent ends of said three spacing members 20 being slidably interfitted by the provision of grooves formed in certain of said ends adapted to receive the other of said ends and thus hold the ends of said additional spacing member from movement in three directions 25 transversely to its longitudinal axis, said closure wall serving, when secured in place to its adjacent companion walls, to hold said last mentioned spacing member from movement in a fourth direction.

7. A packing case having an internal spacing and reinforcing frame in close contact with the four side walls of the case, at least two members of the frame being secured to opposite side walls of the case, and at least 30 one member being freely removable out-

wardly from the other members when its corresponding side wall is released, but secured against movement in either direction parallel to the plane of said wall by means on the frame members.

Signed at Chicago, Illinois, this 15th day of February, 1930.

CHARLES W. GERLACH.
